Primary Examiner — Nathaniel D. Buckner(74) *Attorney, Agent, or Firm* — LEASON ELLIS LLP(57) **CLAIM**

The ornamental design for a charger, as shown and described.

DESCRIPTION

FIG. 1 is a top side isometric view of our new design for a charger.

FIG. 2 is a front side elevation view thereof.

FIG. 3 is a back side elevation view thereof.

FIG. 4 is a left side elevation view thereof.

FIG. 5 is a right side elevation view thereof.

FIG. 6 is a top side plan view thereof; and,

FIG. 7 is a bottom side plan view thereof.

The broken lines in the figures depict portions of the charger which form no part of the claimed design.

1 Claim, 5 Drawing Sheets(56)
